Primary Examiner — Michael A. Pratt
Assistant Examiner — Michelle E Wilson(57) **CLAIM**

The ornamental design for a laundry washing module, as shown and described.

DESCRIPTIONFIG. 1 is a front perspective view of a laundry washing module showing our new design; and,
FIG. 2 is a front perspective view of the laundry washing module of FIG. 1, with a wash drawer of the laundry washing module in an opened position.

The broken lines are showing portions of a laundry washing module that form no part of the claimed design.
